DRAFT RIGGING

Donald S. Barrows, Rochester, N. Y., assignor to
 The Symington Company, New York, N. Y., a
 corporation of Maryland

Application February 14, 1933, Serial No. 656,722

11 Claims. (Cl. 213—31)

This invention relates to draft rigging and, more particularly, to friction draft gears adapted for use on railway vehicles.

The principal object of my invention, generally considered, is to provide friction draft gears or cushioning mechanism especially adapted for railway service and having housings or casings so slotted that they are adapted to receive draft keys for connection with associated sills, whereby they give a cushioning action different in buff than on draft, or, if the gear is of the single-ended type, said housing need not be slotted, as it might then be employed with a conventional front follower.

Another object of my invention is the provision of cushioning mechanism adapted for use with railway draft rigging and involving a spring and friction barrel which may be closed at one end and open at the other, or open at both ends, said open end or ends being formed with outwardly diverging friction surfaces, friction shoes engaging said surfaces, a follower engaging the ends of said shoes and provided with an extension between said shoes, said extension terminating in a portion functioning as an intermediate follower, resilient means being provided between said extension and the inner surfaces of said shoes in the pockets between the outer and intermediate follower portions for urging said shoes into engagement with the friction surfaces of the housing, release springs being provided between the intermediate follower portion or portions and either the end wall of the housing or web portions or abutments provided for said springs intermediate the ends of said housing.

A further object of my invention is the provision of a yoke-acting device formed with arms slotted for receiving horizontal draft keys, provided at its rear end with a transverse connecting portion adapted to engage a backstop, and at its front end with a transverse upper connecting portion adapted to function as a striking casting, and a lower forward connecting portion adapted to support a wear block which, in turn, is adapted to engage and support an associated coupler.

A still further object of my invention is the provision of a friction draft gear adapted for use on a railway vehicle and comprising a housing, friction shoes engaging outwardly diverging friction surfaces on said housing, and a combined member functioning as a carrier for the resilient means acting on said shoes, and outer and intermediate follower members, the intermediate follower portion of said combined member being integral with said member and normally acted on

by release springs, and adapted, upon release, to start moving outwardly prior to movement of the associated friction shoes in order to facilitate release of said shoes.

Other objects and advantages of the invention relating to the particular arrangement and construction of the various parts will become apparent as the description proceeds.

Referring to the drawings illustrating my invention, the scope whereof is defined by the appended claims:—

Figure 1 is a vertical longitudinal sectional view of one embodiment of my cushioning mechanism shown partly in side elevation and assembled with railway draft rigging embodying my invention and disposed between the sills of a railway vehicle.

Figure 2 is a fragmentary plan of the mechanism shown in Figure 1 with portions of the associated rigging and sills shown in horizontal section.

Figure 3 is a transverse sectional view on the line 3—3 of Figure 1, looking in the direction of the arrows.

Figure 4 is a transverse sectional view on the line 4—4 of Figure 1, looking in the direction of the arrows.

Figure 5 is a perspective view of the yoke-acting means shown in Figures 1 and 2.

Figure 6 is a partial vertical longitudinal sectional view and partial side elevational view of another embodiment of my cushioning mechanism.

Figure 7 is a fragmentary plan of the mechanism shown in Figure 6.

Figure 8 is a transverse sectional view on the line 8—8 of Figure 6, looking in the direction of the arrows.

Figure 9 is a horizontal sectional view on the line 9—9 of Figure 6, looking in the direction of the arrows.

Referring to the drawings in detail, like parts being designated by like reference characters, and first considering the embodiment of my invention illustrated in Figures 1 to 5, inclusive, there is shown a double-ended series friction draft gear or cushioning mechanism 1, particularly adapted for use on railway vehicles, and preferably designed so that it will fit into a draft gear pocket of normal size. In the embodiment shown, it is of a length corresponding with that of a draft gear pocket of standard size allowing for the increased coupler travel provided.

The gear preferably comprises an intermediate friction element, in the form of a spring barrel 55

or housing 2, with its ends open and formed with outwardly diverging walls 3 providing inclined friction surfaces 4. Received between said walls 3 are wedges or friction shoes 5 having surfaces 6 desirably formed with lead inserts 6', or other means for providing smooth action or obviating sticking, said surfaces normally engaging the friction surfaces 4 on the housing 2. The shoes 5 are desirably formed generally U-shaped 10 in transverse section, as shown most clearly in Figure 2, the side flange portions 7 of which lie on either side of, and embrace, resilient means 8 which, in the present embodiment, take the form of curved plate springs. The curved plate springs 8 are, in turn, received in pockets 9 provided in combined members 10, said members 10 each having an outer or follower portion 11, an intermediate or wedge-shaped spreader portion 12, and an inner or intermediate follower portion 13, all of said portions being preferably integral and forming a carrier for the springs 8 and friction members 5.

If desired, the individual spring plates forming the resilient means 5 may be provided with 25 nibs or interlocking corrugations 14, like the springs shown in the Suckow Patent No. 1,884,913, of October 25, 1932, with those on the innermost spring plates received in corresponding 30 grooves or indentations in the spreader or wedge-shaped portion 12 of the combined member 10, thereby preventing undesired lateral movement of said spring plates and consequent gouging of the walls or flanges 15 which shroud the combined member 10 and serve to rigidify 35 the connection between the parts thereof, as well as completing the pockets 9 which receive the curved plate springs 8.

The release of the gear 1 is desirably effected by relatively long coil springs 16 acting between 40 substantially triangular web portions 17 connecting adjacent walls of the housing 2 at the corners thereof and spring caps 18 formed with spring centering collars 19 and, in turn, centered on lugs 20 extending inwardly from the intermediate follower portions 13 of the combined 45 members 10. The webs or abutment portions 17 are also desirably provided with spring centering collars 21, and the webs or abutments for the release springs 16 for the member 10 at one end 50 of the gear are disposed in diagonally opposite corners of the housing and spaced farther from the end of the housing receiving the associated member 10 than the other end of said housing, thereby allowing for a relatively great length of 55 springs. The springs 16 acting on the member 10 at one end of the housing 2, and their abutment webs 17 are, of course, staggered with those acting on the member 10 at the other end of the housing, or disposed in the remaining corners of 60 said housing, as shown most clearly in Figure 4, whereby the springs 16 acting on the combined members 10 at one end of the housing overlap the corresponding springs 16 acting on the members 10 at the other end of the housing.

In order to provide for limiting movement of 65 the housing 2 with respect to the sills 22 between which it is disposed, said housing has its side walls 23 provided with slots 24 normally receiving a horizontal draft key 25 extending between the 70 upper and lower sets of springs 16, the ends of which are, in turn, normally received in slots 26 in cheek plates 27 connected to the sills 22. In order to make the gear 1 self-contained, the combined members 10 are desirably connected by a 75 bar or bolt 28, the threaded ends of which pass

longitudinally through corresponding apertures in the spreader portions 12 of the members 10 and receive washers 29 and/or nuts 30 for limiting outward movement of said members 10. The bar or bolt 28 is looped or slotted at its central portion, as indicated at 31, to register with the slots 24 in the housing and receive the key 25, thereby providing for centering said rod 28.

The gear 1 is desirably supported between the sills 22 by means of carrier irons 32 and 33. The 10 ends of the carrier iron 32 are desirably connected to the lower flanges 34 of the sills 22 by means of bolts 35, and nuts 36, to allow for ready removability, while the carrier iron 33, which may be used as a more or less permanent connection between the sills, may be desirably connected there-to by means of rivets 37.

To effect the actuation of the gear 1, a combination yoke-acting device 38 is provided, said device comprising side arms 39 connected at their 20 inner or rear ends by a transverse portion 40, which normally abuts a backstop and center filler casting 41, which connects intermediate portions of the sills 22. The outer end portions of the arms 39 are desirably integrally connected at 25 their upper portions by a relatively strong transverse portion 41 adapted to function as a striking casting or stop for the associated coupler 42. The outer end portions of the arms 39 are also preferably integrally connected by a transverse 30 tie portion 43, desirably provided with a notch 44 at its central portion, to facilitate application and removal of the coupler 42 which may have a stem 45, the rear portion of which is enlarged or provided with a swivel butt, as illustrated in 35 Figures 1 and 2. The transverse portion 43 is desirably formed to receive a carrier or wear block 46 which may interlock in place by having one end provided with a tongue 47 received in a corresponding notch 48 in a corresponding arm 39, 40 the other end provided with a notch 49 corresponding with the notch 48 in the opposite arm 39, said notches cooperating to provide a pocket 50, normally receiving a locking block 51, desirably held in place by means of a cotter 52 extending transversely through the corresponding leg 53 of the block 46, the locking block 51 and the corresponding arm 39 of the yoke-acting device 38. On account of the notch 44 in the transverse portion 43 and the legs 53 extending from 50 the body of the block 46, the body of said block is spaced a considerable distance above the notched portion 44, thereby serving to support the stem of the coupler 42 at the desired elevation. In order to provide a block 46 which is 55 strong but relatively light in weight, the legs 53 are desirably connected by the extended flange portion 54 of the inverted U-shaped body portion of the block 46.

The yoke-acting means 38 is supported adjacent its inner end on the key 25 which passes through slots 55 in the arms of said member 38. The outer end of said yoke-acting means desirably slides on a member 56 which is preferably a casting which embraces the outer end of 65 the yoke-acting means or yoke 38 and the stem of the coupler 42, and connects the sills 22 adjacent the end sill 57. The draft sill front end casting 56 carries what may be considered as the remnant 58 of a striking casting at its upper 70 portion and the lower portion 59 provides a flat surface of relatively great area on which the lower surface of the member 43 is adapted to slide.

The draft sill front end casting has rearwardly 75

extending ears 60 connected to the webs of the sills 2 and bifurcated to provide what corresponds with the front ends of slots 61 in the cheek plates 27, said cheek plates, therefore, 5 terminating in open-ended slots or notches which, together with the front end casting notches, complete the front slots 61 which receive the draft key 62 which serves to connect the coupler 42 to the yoke 38, said key 62 also extending through 10 a slot 63 in the coupler 42, and a slot 64 in the arms 39 of the yoke 38.

In addition to the rear slot 26 and the front slot 61, each cheek plate 27 may be provided with 15 an intermediate slot 65 adapted to receive the key which would support the standard or Farlow front follower used with a single-ended gear, or one of normal length.

The operation of the gear of the present embodiment may be as follows, although it will be understood that, if desired, the gear may be used 20 in a different manner, or one bringing the entire capacity into action under both draft and buffing forces. When draft force is applied to the coupler 42, said force is transmitted through the key 25 to the yoke 38, thereby effecting a compression 25 of the rearmost mechanism or rear contractible wedge member of the gear by forward movement of the rear follower or combined member 40, forcing the rear friction shoes 5 into the housing 2, 30 compressing the curved plate springs 8 and the corresponding relatively long release springs 16, it being understood that the housing 2 is prevented from forward movement by the connecting draft key 25, which passes through the slots 24 35 in the housing, corresponding slots 55 in the arms 39 of the yoke, and the corresponding slots 26 in the cheek plates and/or draft sills of the vehicle. Inasmuch as the yoke moves forwardly with the coupler on draft, drooping of the coupler is minimized because it is supported on a 40 block which moves forwardly therewith. The release features are desirably those described more in detail with reference to Figs. 6 to 9, inclusive.

Under the action of buffing forces, however, the coupler 42 engages the front follower or combined member 40, pushing it and the friction shoes 5 and plate springs 8 associated therewith into the housing 2, while simultaneously moving 45 said housing rearwardly over the rear friction elements 5 and their springs 8, which rearward movement is permitted on account of the rearward elongation of the slots 55 in the yoke arms and the slots 26 in the cheek plates. During this 50 action, the rear follower or combined member 40 is held from rearward movement by means of the backstop 41. It will, therefore, be seen that full compression of the gear is permitted under the action of buffing forces, not only providing 55 for increased buffing capacity, but for a coupler travel equal to the sum of the travel permitted by the friction elements at each end of the gear. Although, for convenience, the gear is preferably made so that the travel provided by each end is 60 identical, yet this is not essential, as the travel may be different at each end of the gear, and the capacity of each end may be the same or different, as desired.

When the buffing force on the coupler is released, the springs 16 first act on the intermediate follower portions 43 of the combined members 40 to start the release action. Said combined members and springs 8 then slide out of the housing 2 until the inner ends of the friction 65 shoes 5 are engaged by the combined members 40,

thereby effecting the desired outward movement of said shoes. This action facilitates release of the gear as the friction of the convex sides of the springs 8 on the inner surfaces of the friction elements 5 is less than the friction of the outer surfaces of the elements 5 on the outwardly diverging friction surfaces of the housing. 5

Referring now to the embodiment of my invention illustrated in Figures 6 to 9, inclusive, a gear 1^a is illustrated, the features of which are very 10 similar to the gear 1 of the first embodiment. Inasmuch as the gear 1^a is illustrated on a larger scale than the gear 1, the features of the gear 1^a will now be described in detail and compared 15 with those of the gear 1.

The gear 1^a preferably comprises a spring barrel or housing 2^a which is shorter than the housing 2 of the gear 1, because the gear 1^a is merely a single-ended gear, or one adapted to interchange with a draft gear of normal size for use 20 with rigging of conventional character, such, for example, as that illustrated in Figure 2 of the Martin Patent No. 1,803,911 of May 5, 1931. In other words, the gear 1^a is adapted for use with a standard front follower such as indicated by 25 the reference character 49 in Figure 2 of the Martin patent referred to and is not adapted to give differential cushioning action like the gear 1 of the first embodiment.

The housing 2^a is open at one end and formed 30 at said open end with outwardly diverging walls 3^a providing inclined friction surfaces 4^a. Received between said walls 3^a are wedges or shoes 5^a having friction surfaces 6^a normally engaging the friction surfaces 4^a on the housing 2^a. The 35 shoes 5^a are desirably generally U-shaped in transverse section, as shown most clearly in Figure 8, the side flanges 7^a of which lie on either side of or embrace resilient means which, in the present embodiment, have the form of curved 40 plate springs 8^a. The curved plate springs 8^a are, in turn, received in pockets 9^a provided in the combined member 10^a.

The member 10^a involves three parts, the outer follower portion 11^a, the intermediate shim or 45 spreader portion 12^a, and the inner or intermediate follower portion 13^a, all of said portions being preferably integral and connected by side wall or flange portions 15^a. The side wall portions 15^a are desirably notched or cut away, as 50 indicated at 67, to receive the flanges 7^a of the friction shoes 5^a, while allowing a small amount of clearance 68 therebetween. In order to prevent the concave end portions 69 of the springs 8^a from gouging the combined member 10^a, angular wear members 70 may be employed, if desired. 55

The spreader portion 12^a of the present embodiment is in section like an isosceles triangle with the base incorporated in the follower portion 11^a. Inasmuch as the follower portion is 60 pocketed, as indicated at 71, a considerable longitudinal distance is gained inside of the gear 1^a, thereby making it possible to use longer coil release springs 16^a which act between the intermediate follower portion 13^a and the end wall 65 portion 72 of the housing. The two groups of spring leaves, that is, one group on either side of the wedge or spreader portion 12^a, are disposed with their concave sides facing one another so that the convex sides engage the inner surfaces 73 of the friction shoes 5^a, which surfaces are normally parallel to the surfaces of the wedge-shaped spreader portion 12^a, so that the springs 8^a are disposed between generally parallel surfaces and 70 engage the surfaces 13 of the friction shoes 5^a. 75

at the approximate centers thereof. The surfaces 73, as will be noted, are at a slight angle to the friction surfaces 6^a of the friction shoes 5^a.

By forming the combined member 10^a, as described, not only do we have a structurally adequate intermediate follower, but through the space gained by the angular arrangement, there is no serious reduction in gear capacity, as the space taken up by the spreader portion 12^a is practically recovered by the insetting of the surfaces 73 engaged by the springs 8^a between the flanges 7^a.

It will also be noted that both ends of the springs rest in suitable pockets and are relatively immovable with respect to the combined member or follower 10^a. This avoids cutting of the follower as when the flexing of the springs involves relative movement between their ends and the surfaces of associated followers. The angular disposal of the spring groups automatically gives a releasing component, equal to the spring pressure times the sine of the angle of inclination of the spreader portion 12^a, which always acts to force the center wedge out. This, it will be noted, provides a releasing means independent of the release springs 16^a. On account of the clearance 68 between the inside integral follower portion 13^a and the small ends of the wedges 5^a, an initial release movement may take place, causing the member 10^a to move outwardly until it closes up the clearance 68 and engages the wedges 5^a, thereby facilitating the release thereof. This results in what might be termed a quick release of the gear as the follower member 10^a and the springs 8^a will tend to move before the friction wedges 5^a start to release, on account of the friction between the convex surfaces of the springs and the engaged surfaces 73 on the wedges being less than the friction between the surfaces 6^a and 4^a. The reason for this will be readily apparent, as it is obvious that the smooth convex steel spring surface will tend to slide more readily on the surfaces 73 than the flat surfaces 6^a and 4^a of the corresponding castings will tend to slide one upon the other.

In order to make the gear self-contained, a central bolt 28^a is provided, the head of which is desirably inset in a pocket 74 in the end wall 72 of the housing, and the threaded end extends through the intermediate follower 13^a and spreader 12^a to project into a pocket 75 in said spreader, allowing for the application of a nut 30^a.

To facilitate application of the gear, the length is desirably initially made less than the pocket in the car in which it is received, by employing a washer 16 of wood or other material of a destructible self-eliminating character, and is initially applied between the nut and the surface of the spreader portion 11^a against which the nut would normally bear. After the gear is placed in service, the washer will be destroyed and eliminated in a short while, thereby allowing the gear to assume its normal length.

From the foregoing disclosure, it will be seen that I have developed a draft gear having important advantages, and the features of said gear may be employed either in a single-ended gear of normal length, or a double-ended gear adapted for use with special rigging to give a different amount of cushioning action for buffing forces than for draft forces. An important manufacturing advantage of the type of gear disclosed is the use of the single incline provided by the walls 3 or 3^a, as the case may be, on which are produced friction surfaces which can be readily

cleaned and gauged. For the same reason, there are no offsets in the wedges or wedge shoes 5 or 5^a themselves, and the same advantages are gained.

Although preferred embodiments of my invention have been illustrated, it will be understood that modifications may be made within the spirit and scope of the appended claims. 5

I claim:—

1. In railway draft rigging, in combination with draft sills, a backstop connecting said sills, a 10 coupler, and yoke-acting means normally engaging said backstop so as to be stationary on buff, a friction draft gear comprising a housing with cushioning mechanism at each end, said yoke-acting means embracing said housing and cushioning mechanism to actuate the rear mechanism on draft, said coupler, yoke-acting means, housing and sills being formed with slots, a housing key passing through said slots in said housing, yoke-acting means and sills and another key passing through corresponding slots in said coupler, yoke-acting means and sills, said sill slots being elongated rearwardly of the normal position of the housing key to permit rearward movement of the housing on buff, while holding it stationary on draft, whereby the cushioning mechanisms at both ends are operated on buff but only that at the rear end on draft, said yoke-acting means being continued forwardly at the sides of the coupler and connected at its front end by an 30 integral portion functioning as a striking casting, and a coupler carrier resting on portions of said yoke-acting means beneath said striking casting portion for supporting said coupler. 20

2. In railway draft rigging, in combination with 35 draft sills, a backstop connecting said sills, a coupler, and yoke-acting means normally engaging said backstop so as to be stationary on buff, a friction draft gear comprising a housing open at both ends, friction elements cooperating 40 with said housing at each end, said yoke-acting means embracing said housing and friction elements for actuating the rear elements on draft, said coupler, yoke-acting means, housing and sills being formed with slots, a key passing through 45 said slots in said housing, yoke-acting means and sills, the slots in said sills being normally engaged by said key at the front ends and formed so as to allow rearward movement of said key from normal position, whereby the friction elements at 50 both ends are actuated on buff, but only those at the rear end on draft, said yoke-acting means being connected to the coupler, by a key slideable rearwardly in the former on buff, and extending forwardly of said connection and formed with a 55 portion underlying said coupler for the support thereof, whereby said coupler is supported during a draft movement by forwardly moving means.

3. Cushioning mechanism comprising a housing slotted adjacent the center thereof for receiving a connecting draft key, substantially triangular webs connecting adjacent wall portions at diagonally opposite corners, those at one pair of diagonally opposite corners being offset longitudinally in one direction from the center of the 60 housing and those disposed at the other pair of diagonally opposite corners being offset longitudinally in the other direction from the center of said housing, the ends of said housing flaring outwardly to provide inclined friction surfaces, friction elements received in each end of said housing and presenting correspondingly inclined friction surfaces for engagement with the friction surfaces of the housing, resilient means disposed between said friction elements at each end of the 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 - housing, carriers for said resilient means, said carriers comprising outer follower portions, intermediate spacer portions for said resilient means, and inner intermediate follower portions, and 5 release springs disposed between said intermediate follower portions and the substantially triangular web portions, said release springs at opposite ends of the housing being alternately arranged so that those at one end engage the diagonally 10 disposed webs farthest from that end of the housing and those at the other end engage the diagonally disposed webs longitudinally spaced from said first-mentioned webs.
4. Cushioning mechanism comprising a housing 15 formed with a slot adjacent the center for receiving a connecting draft key, abutments formed at inside corner portions of said housing, said abutments being arranged in pairs disposed at corresponding longitudinal positions at diagonally 20 opposite corners, those abutments of one pair being offset longitudinally with respect to those of the other pair, the end portions of said housing being provided with inclined friction surfaces, friction elements engaging said inclined 25 friction surfaces at each end of the housing, resilient means acting on said friction elements to keep them in engagement with the friction surfaces of the housing, carriers provided with pockets receiving said resilient means and friction 30 elements, and release springs acting between said abutments and the carriers for effecting release of the gear, the release springs adjacent one end of the housing overlapping those adjacent the other end, thereby providing for relatively long 35 springs.
5. Cushioning mechanism adapted for use with railway draft rigging comprising a housing formed with longitudinally extending walls connected by a transverse wall, a pair of said longitudinally 40 extending walls diverging outwardly at their ends to provide inclined friction surfaces, friction shoes formed with outer inclined surfaces corresponding with and engaging the friction surfaces on the housing, a combined follower and 45 friction shoe carrier formed with outwardly opening pockets on opposite sides of a wedge shaped portion and receiving said shoes, resilient means received in said pockets and acting on said shoes, the inner portion of said carrier forming an intermediate follower, and release springs disposed 50 between said intermediate follower portion and the transverse wall of the housing.
6. Cushioning mechanism comprising a housing having inwardly converging opposed flat interior friction surfaces, a pressure-transmitting member movable inwardly of the housing, said member having flat abutment surfaces on opposite sides thereof converging inwardly of the mechanism, spring resistance means opposing inward movement of the pressure-transmitting member, curved plate springs engaging the abutment surfaces of the pressure-transmitting member, friction shoes disposed between said curved plate springs and the friction surfaces of the 65 housing, said plate springs having sliding frictional engagement with the shoes, and said shoes having sliding frictional engagement with the friction surfaces of the housing.
7. Cushioning mechanism comprising a housing 70 having opposed interior converging friction surfaces and a contractible wedge member movable into said housing and comprising a carrier portion with a wedge shaped body and laterally extending end portions forming pockets on opposite sides of said body, plate springs disposed
- in said pockets, and shoes engaged by said springs and, in turn, engaging the friction surfaces of said housing.
8. Cushioning mechanism adapted for use with railway draft rigging comprising a housing 75 formed with longitudinally extending walls, a pair of said walls diverging outwardly at their end portions to provide inclined friction surfaces, friction shoes formed with outer inclined friction surfaces corresponding with and engaging the friction surfaces of the housing, actuating springs for said shoes, a carrier for said shoes and springs comprising an outer follower portion, an inner follower portion, and a tapered spreader portion, said member being shrouded by longitudinal webs connecting said follower and spreader portions and providing pockets receiving said shoes and springs.
9. Cushioning mechanism adapted for use with railway draft rigging comprising a housing 20 formed with longitudinally extending walls, a pair of said walls having diverging portions adjacent one end providing friction surfaces, a combined member comprising integrally formed longitudinally spaced follower portions 25 connected by an intermediate tapering portion and providing laterally opening pockets, curved plate springs received in said pockets, friction shoes provided with flanges embracing said springs, and outer friction surfaces engaging the friction surfaces of the housing, said shoes being shorter than the space between the limiting portions of the combined member providing clearance at opposite ends of said shoes, whereby upon movement of said combined member, the springs therein slide on said shoes until the clearance is taken up and then said shoes slide on the friction surfaces of the housing.
10. Cushioning mechanism comprising a housing 30 having opposed interior converging friction surfaces and a contractible wedge member movable longitudinally into and out of said housing, said member comprising an intermediate portion with inclined sides and laterally extending portions at opposite ends of said intermediate portion forming laterally opening pockets, shoes 35 engaging the friction surfaces on the housing, and resilient means disposed between the inclined sides of said portion and said shoes for urging the latter into engagement with said friction surfaces.
11. In railway draft rigging, in combination with draft sills, a backstop connecting said sills, a coupler, and yoke-acting means normally engaging said backstop so as to be stationary on 40 buff, a friction draft gear comprising an intermediate friction element and front and rear friction elements engaging end portions of said intermediate friction element, said yoke-acting means embracing said gear so as to actuate the rear friction elements on draft, said coupler, yoke-acting means, intermediate friction element and sills being formed with slots, a key passing through some of said slots for connecting said intermediate friction element and yoke-acting 45 means to said sills, and another key passing through other of said slots for connecting said coupler and yoke-acting means, said sill slots being elongated rearwardly of the normal position of the keys to permit rearward movement of 50 the intermediate friction element on buff, said yoke-acting means comprising a portion adapted to function as a striking casting and another portion beneath said striking casting portion adapted to function as a coupler carrier,

said coupler carrier portion being spaced from the striking casting portion a distance sufficient to allow for the application and withdrawal of the stem of said coupler, and a carrier block provided with a tongue at one end fitting in a corresponding notch in said yoke-acting means,

a notch at the other end normally registering with another notch in said means, and a locking device received in said registering notches for holding the carrier block in place.

DONALD S. BARROWS.
